Patented Nov. 22, 1921.

UNITED STATES PATENT OFFICE.

MARK A. HOPKINS, OF BROOKLYN, NEW YORK.

DISH-WASHING MACHINE.

1,398,022.

Specification of Letters Patent. Patented Nov. 22, 1921.

Application filed October 6, 1920. Serial No. 415,108.

To all whom it may concern:

Be it known that I, MARK A. HOPKINS, a citizen of the United States, and a resident of Brooklyn, Kings county, and State of New York, have invented certain new and useful Improvements in Dish-Washing Machines, of which the following is a specification.

The objects of my present invention are to provide a simple and relatively inexpensive apparatus for washing dishes and other culinary utensils, which will be thoroughly efficient in its operation.

In a preferred embodiment of the invention, the dishes or other articles are supported in a rotating rack or basket and are successively subjected, in the rotation of the rack, to a column of cleansing fluid projected upwardly over the same, by a propeller supported eccentrically beneath the rotating rack.

The invention involves certain other novel features of construction, combinations and relations of parts all as will be more fully disclosed in the following specification.

In the drawing accompanying and forming a part of this specification, I have illustrated two different embodiments of the invention, but wish it understood that further modifications may be made without departing from the true spirit and scope of the invention as hereinafter defined and claimed.

In the drawing referred to, Figure 1 is a vertical sectional view of the apparatus.

Fig. 2 is a fragmentary plan and part sectional view.

Fig. 3 is a broken vertical sectional view of a modified form, and

Figs. 4 and 5 are broken plan and perspective views of the rack construction.

The apparatus comprises a casing or container 5 having a close-fitting removable cover 6 and within which there is suitably journaled a basket or plate rack 7.

In the present disclosure this basket is shown as supported by a shaft 8, said shaft in the first form illustrated, Figs. 1 and 2, being supported at its lower end in a step bearing 9 and engaged at its upper end in a bearing 10 carried by the brace 11 extending radially inward from one side of the casing.

In the second form of the invention illustrated, (Figs. 3 and 4) the shaft is wholly

supported in an elongated bearing 12 provided in the bottom of the casing.

The basket 7 provides a carrier for the plates and other relatively large articles and for the small articles, I have illustrated a tray 13 having a central hub 14 by which it is removably engaged over the upper end of the supporting shaft 8.

In the bottom of the casing and at one side of the axis of the dish carrier, there is journaled a propeller 15, or the like, for forcing a column of the cleansing fluid up over the articles as they are brought above the same in the rotation of the carrier. This propeller is conveniently driven by an electric motor, such as I have indicated at 16, it being shown as directly engaged on the motor shaft 17 which extends through a suitable stuffing box 18. I have shown this motor as detachably connected at 19 with the pedestal 20 which forms the base or support for the machine. This relieves the casing of the weight of the motor and enables the removal of the motor, without disturbing other parts of the machine. To facilitate such removal, the motor shaft may have a detachable coupling therein, such as I have indicated at 21.

The carrier is rotated in the first form of the invention shown, by directly gearing the same to the motor shaft through gear 22 and pinion 23, the first being secured on the carrier shaft 8, and the latter on the motor shaft 17. This gearing is so proportioned and arranged as to produce a relatively slow rotation of the carrier and a relatively rapid rotation of the propeller, the speed of the latter being sufficient to drive a forceful column of the cleansing liquid up over the dishes, etc., passing thereover.

In the modified form of the invention shown in Figs. 3 and 4, the rotation of the carrier is effected from the motor shaft as before, but in this instance, by utilizing the column of water or other cleansing liquid as the connecting medium, the carrier in this form having a series of inclined radially arranged paddle blades 24 which receive the impact of the water column and convert the carrier into what is in effect a slow motion turbine.

These blades are shown as widened toward their outer ends to increase their effectiveness as paddle blades and in addition to such

function, they serve as rack bars for supporting the plates in inclined relation, it being seen that in placing the plates between these bars, they will naturally assume the desired inclined relation.

In the modified construction, I have also shown the propeller as operating in or above a well or depression 26 provided in the bottom of the casing. This enables the propeller to throw a full column with only a relatively small supply of water in the casing.

In using the apparatus, the dishes are preferably stacked in the lower tray in inclined relation, as indicated, and cups, glasses, silverware and the like are placed also preferably in inverted relation on the upper tray. For a cleansing fluid, hot soapy water is usually sufficient and when a sufficient amount of this has been placed in the casing, the motor is set into operation to drive the propeller and from that the rotary carrier. As the carrier rotates, successive sections of the dishes, etc., are brought into the direct range of the column projected upwardly by the propeller and hence all articles are in effect individually treated to the cleansing action of the column of hot water. This action may be repeated as many times as thought necessary for simply continuing the apparatus in operation.

What I claim is:

1. Dish washing apparatus comprising a casing, a dish carrier rotatably supported

therein on a substantially vertical axis, a propeller supported at a fixed point beneath the carrier on a substantially vertical axis and eccentric to the axis of the carrier, means for operating said propeller and means by which the carrier is rotated by liquid from the propeller to thereby bring articles stacked on the carrier successively into the range of direct influence of the propeller.

2. The combination of claim 1, wherein the driving means for the carrier includes inclined blades on the carrier forming a rack for the dishes and operating as paddle blades when in the range of the stream projected by the propeller.

3. The combination of claim 1, wherein the casing is provided with a well in the bottom thereof and over which the propeller is located.

4. Dish washing apparatus comprising a casing, a dish carrier rotatably supported therein on a substantially vertical axis and provided with inclined blades forming a rack for supporting dishes in inclined relation and means for projecting a stream of water, from a fixed point beneath the carrier and at one side of the axis of the carrier, upwardly against the inclined blades and the plates supported thereby, so as to thereby rotate the carrier.

In witness whereof I have hereunto set my hand this 2nd day of October, 1920.

MARK A. HOPKINS.
